UNITED STATES PATENT OFFICE.

JAMES GODFREY, OF PITTOCK, AND SAMUEL NICHOL, OF CARRICK, PENNSYLVANIA.

FURNACE.

Application filed August 7, 1922. Serial No. 580,353.

To all whom it may concern:

Be it known that we, JAMES GODFREY and SAMUEL NICHOL, both citizens of the United States, residing at Pittock and Carrick, respectively, in the county of Allegheny and State of Pennsylvania, have invented new and useful Improvements in Furnaces, of which the following is a specification.

This invention relates to furnaces, and more particularly to what I term a three-way furnace specially adapted for heating slabs, ingots, etc.

One of the main objects of the invention is to provide a pit furnace which may be readily constructed at comparatively small cost and is of simple operation. A further object is to provide a furnace in which the draft can be controlled so as to flow in either direction through the furnace from end to end thereof or from both ends to the middle of the furnace. A further object is to provide a furnace so constructed and arranged as to effect a material saving in fuel as compared to the furnaces at present used for heating slabs, this furnace permitting any kind of fluid fuel desired to be used to advantage. Further objects will appear from the detailed description.

In the drawings:—

Figure 1 is a top plan view of the furnace;

Figure 2 is a section taken substantially on line 2—2 of Figure 1;

Figure 3 is a section taken substantially on line 3—3 of Figure 1;

Figure 4 is a section taken substantially on line 4—4 of Figure 1;

Figure 5 is a section through one of the end checker-chambers and associated parts taken at right angles to Figure 2.

In constructing the furnace we provide a main casing 1 of rectangular shape which is divided, by means of arches 2, into four pits 3. Each pit is closed by a removable cover 4 supported upon arches 2, these covers permitting the billets to be heated to be placed in the respective pits. The floor of the body portion of casing 1 forming the pits 3 is preferably covered with a thick layer 5 of slag which is melted upon a layer 6 of brick supported upon a concrete base 7. To permit removal of the slag, when desired, one wall of casing 1 is provided with a plurality of openings 8. We have found the slag floor 5 very efficient as it retains the heat and is much more quickly installed

than the carbon covering or floor used in furnaces of this general type. In addition, the slag does not cost anything whereas the carbon used for this purpose is often rather expensive.

At each end of casing 1 we provide a checker-chamber 9 within which is built a checker 10 in a known manner. This chamber is closed by an arched cover or roof 13. Burners 14 of any suitable or preferred type project through cover 13 at an angle of approximately 45° thereto, the inner ends of these burners being positioned in the space between the end arch 2 and a bridge wall 15 extending across casing 1, this bridge wall being preferably provided with a chill plate 16 in the form of a hollow casting which extends the full width of casing 1 and is open at both ends to permit free circulation of air for the purpose of cooling bridge wall 15. Midway between checker-chambers 9 we provide a central checker-chamber 17 within which is a checker 18 above which are arches 20 disposed transversely of casing 1. Arches 20 support central bridge walls 21 each of which is provided with a chill plate 22 similar to chill plate 16. The space between arches 20 and bridge walls 21 forms an air duct or passage 23 which is covered by a cap plate 24 supported upon spaced tiles 25 the spaces between which establish communication between the interior of casing 1 and flue 23. At each side of casing 1, and above each of the bridge walls 21, we provide a burner 26 of any suitable or preferred type, these burners being disposed horizontally and in alignment transversely of the casing.

A conduit 27 extends from each of the end checker chambers 9 and communicates with passages 28 in a draft control casing 29. Each of these passages 28 communicates, by means of an opening 30, with a sheet metal hood 31 which is secured to the casing 29 and extends above passages 28 and a central passage 32 which communicates, by means of a duct 33, with a stack 34. A control valve 35 is mounted within hood 31 upon a shaft 36 rockably mounted transversely of the hood by means of which the valve can be turned into either extreme position for establishing communication between either of the air passages 28, selectively, and the air passage or duct 32. Angle strips 37 secured to the hood 31 and the division walls 38 of casing 29 serve to limit

turning movement of valve 35 in either direction and to effectually shut off communication between one of the air passages 28 and duct or passage 32 when the other air 6 passage is in communication with the air duct. By turning the valve 35 into central or vertical position, communication is established between both of the air passages 28 and the air duct or passage 32. Hood 31 10 is provided in its top wall with a central air inlet opening 39 which may be closed by a cover plate 40 suspended in any suitable or preferred manner by a chain 41.

A central conduit 42 establishes communication between the central checker chamber 17 and a sheet metal hood 43 which is secured to conduit 42 and extends over the upper end of a vertical passage 44 at the outer end of the conduit. This passage 44 is separated 20 by a wall 45 from a vertical passage 46 which communicates at its lower end with a lower flue 47 leading to the stack 34. The hood 43 also extends over the upper end of the vertical passage 46 and a valve 48 similar to 25 valve 35 is secured on a shaft 49 rockably mounted through hood 43 transversely thereof. Angle plates 50 are secured to the hood and on the upper edge of wall 45, these plates serving to limit movement of the valve in 30 either direction and co-operating with the valve to effectually shut off or establish, as the case may be, communication between the passages 44 and 46. Hood 43 is provided in its top wall with a central opening 51 which 35 may be closed by a cover plate 52 similar to plate 40.

The casing 1 is suitably braced by means of tie rods, channel beams, plates etc., and is preferably built of concrete, the arches 2 40 and other parts which are subjected to the direct action of the flames being preferably covered with a coating of any suitable or preferred refractory material. The casing is also provided with suitably placed manholes 45 and doors therefor to permit ready access to the interior of the furnace and the checkers for cleaning, repairs, etc.

When it is desired to fire the furnace from the left to the right, as considered in Figures 50 1, 2 and 3, valve 35 is set in the full line position illustrated in Fig. 4, plate 40 being raised so as to uncover the air inlet opening 39, and valve 48 is set in the dotted line position illustrated in Fig. 3, plate 52 being raised to uncover opening 51. The burners 14 at the left end of casing 1 are then lighted, the burners 26 at the right-hand side of the central arch 2 being also lighted. After this has been done flue 33 is opened by raising 60 stack damper 53 which is vertically slidable across the flue and is held in raised position by a counterweight 54 connected by a cable 55 to the damper, this cable being passed over a pulley 56 supported by a bracket 57 mounted on a wall or supporting structure 58 above

the central conduit 42. Air enters hood 31 through opening 39 and flows through flue 27 to the left-hand end of the casing, this air mixing with the fuel and the resulting products of combustion flowing through casing 1 to the right-hand end thereof and through the right-hand flue 27 to casing 29 and into hood 31 beneath damper or valve 35, the products of combustion then flowing downwardly through air duct 32 and 75 through flue 33 into stack 34. At the same time that this occurs, air enters hood 43 through opening 51 and flows downwardly through the vertical air passage 44 into the central checker chamber, this air flowing 80 upwardly through the checker 18 and passage 23 and into the right-hand portion of casing 1, the air flowing from between the tiles 25 being drawn toward the right-hand end of the casing and through flue or conduit 13 to the stack. When it is desired to fire the furnace from the right end to the left end, the position of valve 35 is reversed, valve 48 remaining in the dotted line position illustrated in Fig. 3. To fire the furnace from both ends to the middle, damper 53 is lowered so as to close flue 33 and valve 35 is turned into central vertical position, the burners at both ends of the casing being lighted. The valve 48 is then turned into 95 the position illustrated in Figure 3. When this has been done air will flow into the casing at the ends thereof by means of hood 31 and conduit 27, the products of combustion being drawn to the center of the casing between tiles 25 and through air duct or passage 23, checker 18, conduit 42, vertical air passage 44, hood 43, air passage 46 and flue 47 to the stack. To fire the furnace from the middle to both ends, valve 48 is turned into the dotted line position illustrated in 105 Figure 3, valve 35 is turned into central vertical position, and plate 40 is lowered into position to close opening 39 of hood 31, damper 53 being raised, burners 26 being lit and burners 14 extinguished. Air flows through opening 51 into hood 43, down passage 44 and through central conduit 42 into and through checker 18, this air mixing with the fuel from burners 26 and the resulting 110 products of combustion flowing from the center of casing 1 toward the ends thereof. The products of combustion then flow downwardly through the end checkers into the end flues or conduits 27, through conduits 27 to casing 29, upwardly through passages 28 into hood 31, downwardly from the hood through central passage 32 to duct 33 and through this duct to stack 34. This provides 115 very simple and efficient means whereby the direction of the draft through the furnace may be readily changed to suit conditions. By having the draft extending throughout the length of the furnace the products of combustion are kept close to the cinder floor 120 125 130

5 which becomes highly heated and co-acts with the burners to effectively heat the ingots or slabs. Also, due to the length of travel of the products of combustion we are enabled to use oil, tar, and similar fuels in the burners 14 and to obtain complete combustion, which effects a material saving in fuel cost. To prevent clogging of the end checkers, each checker chamber is provided 10 with a cinder pocket 59 which serves to catch cinders and other materials and prevent entry of the same into the checker.

What we claim is:—

1. In a furnace of the character described, a casing, checkers at each end of the casing and at the center of the casing, heating means adjacent to said checkers, and means for causing a draft through the furnace from end to end thereof in either 20 direction or from both ends of the casing simultaneously to the center thereof, selectively, the draft flowing through the checkers.

2. In a furnace of the character described, an elongated casing, checkers at each end of the casing, a checker at the center of the casing, heat generating means adjacent the respective checkers, and means for causing an air current to flow from either end of the casing toward the other end, selectively, or from both ends of the casing simultaneously to the central checker, optionally.

3. In a furnace of the character described, an elongated casing, checkers at each end of the casing, a checker at the center of the casing, heat generating devices adjacent the respective checkers, a conduit leading from the central checker, conduits 40 leading from the end checkers, a stack, means for establishing communication between said stack and either one or both of the end conduits, selectively, and means for establishing communication between the 45 stack and the central conduit.

4. In a furnace of the character described, an elongated casing, checker chambers at each end of the casing, and communicating therewith, a checker chamber at 50 the center of the casing and communicating therewith, checkers in said chambers, heat generating devices positioned adjacent to the respective checkers, end conduits com-

municating with the end checker chambers, a central conduit communicating with the central checker chamber, a stack, a duct communicating with said stack, means for establishing communication between either of the end conduits and said duct, selectively, or between both of the end conduits 60 and the duct, optionally, means for closing said duct, a flue communicating with the stack, and means for optionally cutting off or establishing communication between said flue and the central conduit. 65

5. In a furnace of the character described, a main casing, checker chambers at each end and the center of the casing and communicating therewith, a central conduit communicating with the central checker 70 chamber, a draft control casing having upwardly opening lateral and central air passages, a hood extending over the upper ends of all of said air passages and provided with a central air inlet opening, end flues connecting the end checker chambers with the respective lateral air passages of the draft control casing, a stack, a duct connecting said stack and the central air passage of the draft control casing, means for closing 75 said duct, means for closing the air inlet opening of the hood, a valve mounted in said hood and adjustable to establish communication between either one or both of the lateral air passages and the central air 80 passage of said draft control casing, optionally, said draft control casing being further provided with a flue communicating with the stack, the central conduit being provided with two upwardly opening 85 passages separated from each other and communicating with said central conduit and the flue, respectively, a hood extending over the upper ends of said passages of the central conduit and provided with an air inlet opening, means for closing the opening of the second mentioned hood, and a valve mounted in the said second mentioned 90 hood and adjustable to optionally cut off or establish communication between the upwardly opening passages of the central conduit. 100

In testimony whereof we affix our signatures.

SAMUEL NICHOL.
JAMES GODFREY.
